(57)

CLAIM

The ornamental design for a shaping maternity garment, as shown and described.

DESCRIPTION

FIG. 1 is a perspective view of a shaping maternity garment showing my new design.

FIG. 2 is a front view thereof.

FIG. 3 is a rear view thereof.

FIG. 4 is a rear, top, and right side perspective view thereof.

FIG. 5 is a front and left side perspective view of the shaping maternity garment of FIG. 1, showing how the shaping maternity garment would appear when being worn; and,

FIG. 6 is a front view of FIG. 5.
